GONDOLA TYPE RAILWAY CAR CONVERTIBLE FROM CLOSED TO OPEN END CONSTRUCTION

George B. Willard, Winfield, Ill., and Oliver A. Wallace, Wilmington, N. C., assignors to Enterprise Railway Equipment Company, Chicago, Ill., a corporation of Illinois

Application July 25, 1951, Serial No. 238,442

3 Claims. (Cl. 189—46)

The invention relates to an improved type of movable end wall for a railway car and is especially concerned with a so called gondola car having a fixed floor and sides and movable end walls which may be removed to allow the use of the car as an open ended carrier for handling long materials, such as structural beams, fabricated constructions, etc., which ordinarily project beyond the ends of the car. The invention is by way of an improvement on the conventional drop end wall now employed and which comprises an end wall mounted to swing on a horizontal axis to either assume a horizontal position on the car floor or movable to a vertical position to function as the end wall of the car body.

The objects of the invention among others are: To provide an end wall which is swingable on a vertically disposed axis whereby the wall may be moved with comparatively small effort by one man; to provide an end wall pivotally mounted on one of the car sides and to provide a latching and tying means between the said end wall and the opposite side wall of the car; to provide for antifriction supporting means for the swinging edge of the end wall; and to provide for the retention of the end wall in place along the car side wall on which it is mounted when the car is converted to an open ended car.

Other objects of the invention will be apparent from the description hereinafter following.

For full comprehension of the invention reference may be had to the accompanying drawings wherein:

Figure 1 is a vertical end elevational view of a portion of a railway car showing as much of the car construction as necessary to illustrate the improvement, said view showing the swingable end wall positioned to form the end wall of a gondola car, the latching mechanism at the swinging edge of the wall being omitted and the end wall being broken to conserve space.

Figure 2 is a sectional view of the end portion of the car taken along the line 2—2 of Figure 1 and showing the end wall by full lines as positioned in Figure 1 and illustrating by conventional dot and dash lines the position of the end wall of the car when said wall is swung to lie adjacent the side wall on which it is pivotally mounted.

Figure 3 is a vertical sectional view taken through the end wall as seen in a line 3—3 of Figure 1.

Figure 3A is a detached elevational view of the hinge which is secured to the end wall and supports the same.

Figure 4 is a plan view of the end wall as positioned when the car is converted to an open ended car, said view showing the wall in latched relation to the car side with which it is pivotally associated.

Figure 5 is a vertical sectional view taken through the car side wall and end wall as seen on a line corresponding substantially to a line 5—5 of Figure 4.

Figure 6 is an elevational view on an enlarged scale of the upper part of the end wall in closed position adjacent the swinging edge of the said end wall showing the latching mechanism in latching relation with the adjacent car side wall.

2

Figure 7 is a top plan view of the structure shown in Figure 6.

Figure 8 is a fractional view of the end wall and related structure, illustrated in Figure 6, showing the latching mechanism in released position.

Figure 9 is a side elevational view of the latching hook seat employed for retaining the end wall in latched position.

Figure 10 is a top plan view of the seat shown in Figure 9.

Figure 11 is a detached elevational view of one of the toggle links.

Figure 12 is a top plan view of the link shown in Figure 11.

Figure 13 is a vertical side elevational view of the latching bracket on the end wall.

Figure 14 is a top plan view of the bracket shown in Figure 13.

Figure 15 is a side elevational view of the toggle arm.

Figure 16 is a top plan view of the toggle arm shown in Figure 15.

Figure 17 is a fractional front elevational view of the upper portion of the end wall shown in Figure 4 and illustrating the latching mechanism positioned to retain the end wall against the side wall of the car.

Figure 18 is a detached elevational view of the latching hook seat carried by the side wall and shown in Figure 17.

Figure 19 is a front elevational view of the latching hook seat shown in Figure 18 as viewed from right to left.

In said drawings the car structure is indicated by the center sill 10, end sill 11, car side walls shown generally at 12 and 12', floor 13 and transversely extending lower end angle 14. The side walls are reinforced at the top and bottom by beam members as indicated in Figure 5 at 15 and 16 respectively. The upper beam member 15 preferably consists of two angle shaped members 17 and 18 arranged in reverse relation and welded together at 19 to form a Z shaped beam member. The lower beam member 16 is in the form of an angle having one flange 20 secured to the car side and having the adjacent flange 21 extending inwardly laterally.

The floor 13, which preferably consists of a metal plate, is bent upwardly to present flanges 22 for attachment to the car side walls 12 and 12' and underlying said floor are angle shaped members 23 also attached to the car side walls. The car side walls are reinforced at spaced intervals by side stakes 24 and at the corners of the car by hollow posts 25 and 25'.

The posts 25 and 25' are each preferably formed of a plate bent to a U shape and in cooperation with angle members 26 form four sided enclosures. The post 25 has an entrance 27 at one corner as noted by reference to Figure 2. The sides of the U shape are as indicated at 28, 29 and 30 and adjacent wall 30 the U shape is formed with a reversely directed wall section including sections 31 overlying the side walls 12 and 12' and connecting each section 31 and wall 30 is an inclined wall section 32 which has the effect of providing a flared entrance opening for the post 25.

A swinging end wall, shown generally at 33 in Figures 1 through 5, is formed of metal plate flanged at the top, bottom and sides as indicated at 34, 35 and 36, respectively, Figure 5, and the top and bottom margins are further reinforced by angle shaped members 37 and 38. It will be understood that each end of the gondola type railway car is provided with a swinging end wall 33. Since they are of similar construction, only one will be described in detail. The end wall 33 preferably consists of a plurality of panels 39, 40 and 41 united into

a single member by welding as at 42 and the main body of each panel is reinforced by a corrugation 43.

The end wall 33 at each end of the car is pivotally mounted on the end of the side wall 12 to swing about a vertically extending axis 44, Figure 4. For this purpose interengaging hinge brackets are carried by the post 25 and swinging end wall 33 respectively. The brackets carried by the post 25 are indicated at 45 and the associated bracket 46 carried by the wall 33 is preferably formed of a single member, Figures 1 and 3A, extending from the top to bottom of the swinging end wall 33 in one piece. The bracket 46 carried by the end wall 33 includes a base portion 47 disposed in the angle formed by the body of the end wall 33 and the vertically extending flange 36 and said base portion is secured in place by rivets 48, Figure 2. Projecting from the base portion 47 is an extension of the hinge bracket of arcuate form as indicated at 49 which is formed concentrically with respect to the hinge axis 44 to lie adjacent the flared portion 32 of the post 25 throughout the entire range of swinging movement of the end wall 33. A series of hinge lugs 50 is disposed on the concave inner side of the extension 49 and these are spaced vertically to admit therebetween correspondingly formed lugs 51 formed on the brackets 45 and the respective lugs 50 and 51 are apertured for the accommodation of a hinge rod 52 whereby the end wall 33 is supported in swinging relation on the side wall 12. The hinge rod 52 and the encircling hinge lugs 50 and 51 are preferably located within the hollow post 25, to allow for unobstructed sweep of the end wall 33 in its transition from the closed position shown in Figure 2 to the open position shown in Figure 4. The arcuately shaped extension 49 has its outer surface concentric with the vertical axis 44 of the hinge rod 52 and it extends through sufficient angular distance to maintain tangential contact with the inner face of the post 25 throughout the entire swinging movement of the end wall 33.

The end wall 33 is arranged to swing through approximately 90° of movement from its position as shown in Figure 2 to that shown in Figure 4 and is preferably provided adjacent its swinging edge with an antifriction support in the form of a wheel 53, Figure 5, pivotally mounted on an axle 54. The wheel and axle are mounted in a bracket 55 which in turn is secured to the lower portion of the end wall 33.

At the upper margin of the end wall 33 adjacent the swinging edge thereof there is disposed toggle acting latching mechanism, Figures 6 and 7, in the form of a pair of links 56—56, Figures 11 and 12, pivoted at 57 on a bracket 58, Figures 13 and 14, rigidly secured to the end wall. The pair of links 56 is spaced apart to straddle the end wall 33 and they are extended beyond the latter to straddle a keeper bracket or hook shaped member 59, Figures 9 and 10, which is rigidly secured to the car side wall by welding as indicated at 60, Figure 8. Pivoted mounted at 61, Figure 8, between the extended portion of the links 56 is a toggle arm 62 which is formed with an arcuately shaped end 63 arranged to seat in a concave depression 64 formed in hook member 59 whereby the end wall 33 and the car side 12' may be tied together by the toggle acting mechanism and the end wall 33 is thus positioned to function as a tie member of great strength and provides a structure for maintaining the car sides 12 and 12' in spaced relation. The pivotal mounting of the toggle arm 62 is effected by means of trunnions 65, Figure 12, which are formed integrally with the link 56 and constitute the pivot mounting at 57 and 61. The toggle arm 62 is provided with an operating handle extension 66 having a hollow socket portion 67 for receiving an operating bar for effecting a turning movement of the toggle arm 62.

The links 56 and toggle arm 62 are employed for retaining the end wall 33 in position along the car side wall 12 when the car is converted to an open ended car. To

this end a keeper bracket or hook shaped member 68, Figures 18 and 19, is mounted on the inner face of the car side wall 12, Figure 17, for cooperation with the toggle linkage shown in Figures 6 and 7 when the end wall 33 is swung through 90° to the position shown in Figures 4 and 5. The hook shaped seat 68 includes a wall portion 69 attached to the car side wall 12 and an upper hook shaped portion 70 spaced outwardly from the attaching wall 69 and corresponding in shape to the depression 64 of the hook member 59 which, it will be recalled, is carried by the car side wall 12.

A recess 71 is provided in the lower portion of the car side wall 12 as indicated in Figures 4 and 5 for receiving the antifriction mounting 53 when the end wall 33 is positioned against the car side wall 12 as here shown. A housing 72 is secured to the outer face of the car side wall 12 to receive the bracket 55 and its associated wheel 53 and axle 54.

The mounting of the end wall 33 on a pivot to swing on a vertical axis enables rapid conversion of the car from open end to closed end or vice versa by one man with comparatively little effort and with perfect safety. There is no possibility of the wall suddenly dropping as is liable to occur when the wall is moved from a horizontal to a vertical position. The retention of the end wall 33 in a vertical position at all times is of advantage inasmuch as there is not the liability to damage such as takes place when the wall is flat on the floor and lading is dropped thereon.

As shown in Figure 8 the toggle arm 62 is swung in the direction indicated by the arrow 73 to the locking position either with the hook member 59 or the hook member 68. In the locked position, as illustrated in Figure 6, the toggle arm 62 is swung downwardly into an over center toggle locked position where a line 74 connecting the pivot axes 57 and 61 is located below the center 75 of the arcuate end 63. This toggle locking mechanism securely holds the swinging end wall 33 either across the ends of the car side walls 12 and 12' where it secures them in spaced relation and braces the same or in juxtaposition to the side wall 12 where an open ended car construction is provided.

What is claimed as new is:

1. In a railway car having spaced apart side walls and an end wall pivotally mounted adjacent one of said walls to swing on a vertically extending axis to either form the end wall of the car or lie along the side wall with which it is pivotally related, a hollow corner post structure for supporting the pivotal mounting of the end wall, said pivotal mounting including a pivot extending vertically within the confines of the hollow post, said corner post structure having an entrance opening in one side for accommodating the end wall therethrough, said end wall being formed with a wall portion concentrically related to the pivotal axis within said post and adapted to remain in close adjacency to the edge of said entrance opening throughout the entire swinging movement of the end wall.
2. In a railway car having spaced apart side walls and an end wall pivotally mounted adjacent one of the side walls to swing on a vertical axis to form either the end wall of the car or assume a position adjacent the side wall with which it is pivotally related to form an open ended car, a corner post for supporting the pivoted end of the end wall, said post being of hollow formation with a wall of the post having an entrance opening adjacent the end wall, hinge brackets having hinge lugs for the pivot disposed within the confines of the hollow post and secured thereto, a wall section leading from the end wall through the opening in the post and formed with hinge lugs disposed in alignment with the lugs of the brackets, a hinge rod extending through the aligned lugs of the brackets and end wall extension, the said extension of the end wall having its outer face extending on an arcuately shaped contour disposed concentrically with respect to the pivotal axis of the end wall and adapted

to move in close tangential relation to the adjacent edge of the opening of the post, said arcuately shaped face being of sufficient angular extent to maintain adjacency with the edge of the opening throughout the range of swinging movement of the end wall.

3. In a railway car having spaced apart side walls and a four sided post of hollow construction at the end of one of said side walls and including inner and outer walls extending in the general direction of the side walls and having spaced transversely disposed walls, said inner wall having an entrance opening therein extending substantially for the entire height of the post and an end wall having an extension in the form of a hinge bracket structure extending through the opening of the post, said end wall being pivotally mounted to swing on a vertically disposed axis located within the confines of the hollow post, said end wall being adapted to swing on its pivotal axis to either extend across the end of the car and form the end wall of the car or assume a position longitudinally along the side on which it is pivotally mounted to form an open end car, said wall of the hinge bracket structure being of arcuate shape to present an outer convex face and an inner concave face, said outer convex face being concentrically formed with respect to the hinge axis of the end wall and movable in close adjacency to the prox-

5
